US0D1046702S

(12) **United States Design Patent** (10) **Patent No.:** **US D1,046,702 S**
(45) **Date of Patent:** **** Oct. 15, 2024**

(54) **MODEL VEHICLE WHEELIE BAR**

(71) Applicant: **TRAXXAS, L.P.**, McKinney, TX (US)

(72) Inventors: **Jonathan Scott Wood**, Campbell, CA (US); **Trent Collins**, McKinney, TX (US); **Otto Karl Allmendinger**, Rowlett, TX (US); **Adam Cole Ewing**, McKinney, TX (US)

(73) Assignee: **TRAXXAS, L.P.**, McKinney, TX (US)

(**) Term: **15 Years**

(21) Appl. No.: **29/829,421**

(22) Filed: **Mar. 4, 2022**

(51) **LOC (14) Cl.** **21-01**

(52) **U.S. Cl.**

USPC **D21/561**; D12/159

(57) **CLAIM**

The ornamental design for a model vehicle wheelie bar as shown and described.

DESCRIPTION

FIG. 1 is a lower, left, front perspective view of a model vehicle wheelie bar showing our new design;

FIG. 2 is a rear elevation view thereof;

FIG. 3 is a front elevation view thereof;

FIG. 4 is a left side elevation view thereof;

FIG. 5 is a right side elevation view thereof;

FIG. 6 is an upper plan view thereof;

FIG. 7 is a lower plan view thereof;

FIG. 8 is an upper, right, rear perspective view thereof; and,

FIG. 9 is an upper, left, front perspective view of the model vehicle wheelie bar.

In the drawings, the broken lines illustrate portions of the model vehicle wheelie bar that form no part of the claimed design.

1 Claim, 5 Drawing Sheets
